UNITED STATES PATENT OFFICE.

GEORGE B. BRINK, OF DETROIT, MICHIGAN, ASSIGNOR TO TUFTING MACHINE SUPPLY COMPANY, OF DETROIT, MICHIGAN, A CORPORATION OF ILLINOIS.

CUSHION-MOLD.

1,103,477.

Specification of Letters Patent. Patented July 14, 1914.

Application filed February 13, 1913. Serial No. 748,077.

To all whom it may concern:

Be it known that I, GEORGE B. BRINK, a citizen of the United States, residing at Detroit, county of Wayne, State of Michigan, 5 have invented a certain new and useful Improvement in Cushion-Molds, and declare the following to be a full, clear, and exact description of the same, such as will enable others skilled in the art to which it pertains 10 to make and use the same, reference being had to the accompanying drawings, which form a part of this specification.

This invention relates to cushion molds and has in view a special apparatus by 15 which the cushions may be tufted, the buttons may be inserted and the cover and foundation cloth facings may be secured together.

The features of construction and the new 20 and improved results will more fully appear in the specification herein following.

In the drawings:—Figure 1, is a perspective of the parts of the mold separated for the purpose of clearer illustration. Fig. 25 2, is a plan view of the mold. Fig. 3, is a section of the mold. Fig. 4, is a sectional detail of the clencher strip and adjacent parts showing how the tack points are turned back or clenched.

30 The cushions that are intended to be made in this mold are those used in vehicles, although, of course, the mold is adapted for the manufacture of cushions for other purposes and I do not limit myself to a cushion 35 for any particular use.

1 indicates the mold board which is of the shape shown in Fig. 1, that is, an oblong block with a slightly dished upper surface. At 40 equally spaced points on the upper surface of the mold board are located button-holders 2. Into these are placed the button heads with the double stems, as shown at 3 in Fig. 3. The leather or fabric cover 4 is laid over the mold board, the stems of the 45 buttons being put through holes in the cover that have already been cut for that purpose. The allowance of extra cover between the button-holders so that the tufting may be accomplished requires the taking up of some 50 of the cover in other parts in the form of plaits. When the cover has been arranged so that the plaits will fall at designed places, the filler, which I prefer to use in the form 55 of hair 5, is laid upon the cover. The foundation or inner cloth 15 is laid upon the

hair, then the follow-board is pressed down and the stems 3 of the buttons protrude through this inner lining, as shown in Fig. 3. The follow-board 6 is then pressed down upon the inner cloth 15 and the filler 5. This 60 may be accomplished by any mechanical means such as a screw-press or equivalent means. The follow-board 6 is provided with a plurality of perforations 7 that register over the button-holders 2 so that the 65 centers of the perforations and the button-holders register. When the follow-board has been pressed down upon the filler, as shown in Fig. 3, the button-washers, not 70 shown, may be fastened on by turning the stems 3 down upon the button-washers. This accomplishes the tufting of the cushion.

The follow-board 6 carries a pair of struts 8 that are slotted at 9 so that the struts may be used as handles. These struts are cut 75 away at the front and in the feet formed by cutaway portions are dowel-pin holes 10. Adjacent the strut 8 the feet 11 are screwed to the follow-board and these also have dowel-pin holes 12. Referring to Fig. 1, it 80 will be seen that the dowel-pins 13 of the clencher-frame 14 are insertible in these dowel-pin holes.

The inner lining and cover at the front of the cushion are cut sufficiently full so that 85 they more than cover the hair and allow the two to be lapped together and brought up over the clencher-frame 14. This clencher-frame comprises a U-bar of wood into which is set at the upper outside edge a metal strip 90 16. When the cover 4 and the inner lining 15 are lapped together and pulled up over the clencher frame, the two may be temporarily secured in place so as to complete the plaiting of the front facing (which is that 95 part of the cover indicated as 17) by driving the tacks 18 part way into the wood portion of the clencher frame. This temporarily holds the inner lining and the facing portion of the cover in place. The plaitings are then arranged and the tacks 19 are driven down through the border strip 20 and the cover and inner lining, the pins being turned back by the metal strip 16. This 100 operation is shown in detail in Fig. 4, although, as here shown, the operation is being performed on the rear edge of the cushion and inner lining and the clencher strip 21 is a part of the follow-board and is 105 a U-shaped strip which extends substantially 110

around the three sides of the follow-board. The rear facing of the cushion is tacked on wrong side out by the tacks 22 which pierce the cover and the inner lining and are 5 turned back by the metal clencher strip 21. Fig. 3 shows the rear facing in the position which it occupies when it is being tacked on. It will readily be understood that when the cushion is reversed and occupies its position 10 for service that the rear facing 23 holds over the tacks so that the method of attachment is concealed.

What I claim is:—

15 In a cushion-mold, the combination of a follow-board, a plurality of legs on one edge

of the follow board, a leg on each side of the follow-board, the said legs being provided with dowel pin holes, a clencher strip, pins on the under side of the clencher strip fitting into the dowel pin holes to hold the clencher 20 strip in spaced relation with the follow-board, and a metal strip on the upper face of the clencher strip, the said clencher strip being arranged to rest on all the legs.

In testimony whereof, I sign this specification in the presence of two witnesses.

GEORGE B. BRINK.
